UNITED STATES PATENT OFFICE.

VERNON B. PIKE, OF CHELTENHAM, PENNSYLVANIA.

CABLE BENDER.

Application filed August 24, 1923. Serial No. 659,195.

This invention relates to cable benders, and more particularly to lever cable benders designed for use in restricted spaces.

In the cable benders of this type used heretofore the following disadvantages are found: (1) the cable gripping members dent the cable sheath; (2) the cable gripping members frequently slip along the cable, especially when they are widely separated, 10 as is the case in making bends of large radii; (3) the shapes of the tools render it inconvenient to use them in restricted spaces.

The object of applicant's invention is to provide a cable bender which is free from 15 the above mentioned disadvantages.

The invention is embodied in a cable bending device comprising cable gripping shoes carried upon arms of different lengths, a yoke holding the arms in fixed co-relation, 20 and a lever handle adjustable as to length and designed to pivot about the middle of the yoke as a center and to be readily secured in any one of a plurality of positions.

The following detailed description covers 25 the preferred form of cable bender embodying applicant's invention. This description is to be read with reference to the accompanying drawing. Figure 1 of the drawing shows a top plan view of the tool, with a 30 part of the handle shown in section; Fig. 2, a side elevation of the tool, with a part of the handle shown in section; Fig. 3, a side elevation of the pivotal end of the outer member of the handle; Fig. 4, a side elevation 35 of one member of the handle adjusting mechanism, and Fig. 5, a side elevation of another member of the handle adjusting mechanism. Like numerals of reference in the several figures of the drawing designate 40 corresponding parts of the tool.

With reference to the details of the drawing, the cable gripping shoes 1 and 2 are carried on arms 3 and 4, respectively, arm 3 being of greater length than arm 4. The 45 shoes are pivotally attached to their respective arms so as to permit of lateral swinging of the shoes. Thus the shoes adjust themselves to fit the cable. The arms 3 and 4 are joined in fixed co-relation by the yoke 5. This yoke carries a notched arc 6.

The lever handle comprises the outer hollow cylinder 7 and the hollow cylinder 8 of smaller diameter designed to slide within the cylinder 7. The top of the wall of the cylinder 7 carries a plurality of holes, represented by the holes 9 and 10. Within the

cylinder 8 at the end lying nearer the shoes is a strip spring 11 carrying upon its free end an outwardly projecting button 12, and an opening in the wall of the cylinder 8 permits the button to protrude when the spring is in its normal position. Before the handle is extended, the opening 9 in the outer cylinder lies opposite this opening in the inner cylinder wall, and the button 12 projects 60 through both openings, fixing the two cylinders of the handle in the unextended position. When it is desired to extend the handle, the button 12 is pushed in, the cylinder 8 is moved so as to bring the button 12 opposite another opening in the cylinder 7, opening 10, for example, and the spring is then released, allowing the button 12 to engage with the opening 10 of the outer cylinder and thus to secure the two cylinders 65 of the handle in an extended position.

The handle member 7 is forked at the end nearer the shoes (see Figs. 2 and 3). The two prongs of the fork embrace the yoke 5 and the notched arc 6, and the screw 15 80 attaches the member 7 to the yoke 5, passing through the openings 13 and 14 of the fork prongs, and forms a pivot for the member 7. Within the cylinder 7 is a cylindrical member 16, of diameter considerably smaller 85 than the interior of the hollow cylinder 7. This member 16 carries an extension 17 of diameter equal to the interior of the cylinder 7. This portion 17 carries in turn a forwardly projecting tooth 18 designed to fit 90 into one of the notches of the arc 6. The hollow cylinder 19, lying within the hollow cylinder 7 of the handle and surrounding the member 16, serves to prevent dislocation of the body 16-17-18, hereinafter referred 95 to as "the single toothed member". Within the member 19 and bearing on the rear of the single toothed member is a spiral spring 20. The sleeve 21 surrounds this portion of the outer handle cylinder 7. The rivet 22 100 fixes the sleeve 21 to the single toothed member and the member 19, passing through the forward end of the slot 24 in the member 7 (see Figs. 1, 2 and 3). A second rivet, 23, having its heads flush with the outer surfaces of the cylinder 7, forms a backstop 105 for the spiral spring 20 and passes through the rear end of slot 25 in the member 19 (see Figs. 1 and 5). When the sleeve 21 is drawn back (that is, to the right with reference to the drawing), the single toothed member is drawn back with it, disengaging 110

2
the tooth 18 from the notched arc 6, and the spring 20 is compressed. The rivet 22 slides in the slot 24 of member 7, and the slot 25 of the member 19 permits this member to 5 slide past the rivet 23. With the tooth 18 disengaged from the notched arc 6, the handle may be pivoted to any desired position. The sleeve 21 is then allowed to slip forward again, releasing the spring 20 and 10 returning the tooth 18 into engagement with another notch of the arc 6.

The following advantages of applicant's tool over cable benders of this class used heretofore are to be noted: (1) the cable gripping shoes are so formed and so mounted that they adjust themselves to the cable and do not dent it; (2) the distance between the shoes is fixed, and thus slipping of the shoes along the cable during the bending operation is avoided; (3) the handle adjusting means permit the handle to be placed in any one of a plurality of positions suitable for convenient use of the tool in restricted spaces.

It is understood that the above entitled description of the preferred form of applicant's cable bender is submitted for purposes of illustration and does not limit the scope of the invention, which is determined by the appended claims.

30 What is claimed is:

1. A cable bender comprising a plurality of arms of different lengths, a cable gripping shoe on each of said arms, a yoke joining said arms in fixed co-relation, a lever handle adjustable as to length and pivotally attached to the middle portion of said yoke, and means for securing said handle with respect to the axis of said yoke at any one of a plurality of angles within an arc of approximately 180°.

2. A cable bender comprising a plurality of arms of different lengths, a cable gripping shoe pivotally attached to each of said arms so as to allow lateral swing of said shoe, a yoke joining said arms in fixed co-relation, a lever handle adjustable as to length and pivotally attached to said yoke, and means for securing said handle with respect to the axis of said yoke at any one of a plurality of angles within an arc of approximately 180°.

3. A cable bender comprising two arms of different lengths; a cable gripping shoe on each of said arms; a yoke joining said arms in fixed relation to each other; a lever handle adjustable as to length, said handle comprising an outer tube pivotally attached to said yoke, a second tube of smaller size designed to slide within said outer tube, and means for securing said second tube to said outer tube in any one of a plurality of extended positions; and means for securing said outer tube with respect to the axis of said yoke at any one of a plurality of angles within an arc of approximately 180°.

4. A cable bender comprising two arms of different lengths; a cable gripping shoe on each of said arms; a yoke joining said arms in fixed relation to each other; a lever handle adjustable as to length, said handle comprising an outer tube pivotally attached to said yoke, a second tube of smaller size designed to slide within said outer tube and having in its wall a single opening, a strip spring mounted within said second tube, and a button on the free end of said strip spring designed to project through the opening in the wall of said second tube, said outer tube having in its wall a plurality of aligned openings to receive said button in different extended positions of said second tube; and means for securing said outer tube with respect to the axis of said yoke at any one of a plurality of angles within an arc of approximately 180°.

5. A cable bender comprising two arms of different lengths, a cable gripping shoe on each of said arms, a yoke joining said arms in fixed relation to each other, a lever handle adjustable as to length and pivotally attached to said yoke, a notched arc fixed to said yoke and having its center located on the pivotal axis of said handle, a single-toothed member within said handle designed to engage with the notches of the arc, means for sliding said single-toothed member out of engagement with said notched arc, and means for automatically returning said single-toothed member into engagement with said notched arc upon the release of said sliding means.

6. A cable bender comprising two arms of different lengths, a cable gripping shoe on each of said arms, a yoke joining said arms in fixed relation to each other, a lever handle adjustable as to length and pivotally attached to said yoke and having in its wall a longitudinal slot, a notched arc fixed to said yoke and having its center located on the pivotal axis of said handle, a single-toothed member within said handle designed to engage with the notches of the arc, a sleeve surrounding said handle and riveted to said single-toothed member, the slot in the wall of said handle permitting said sleeve and the attached single-toothed member to be drawn away from said notched arc, and a spiral spring within said handle bearing against the rear end of said single-toothed member for automatically returning the latter into engagement with the notched arc upon release of said sleeve.

7. A cable bender comprising two arms of different lengths, a cable gripping shoe on each of said arms, a yoke joining said arms in fixed relation to each other, a lever handle adjustable as to length and pivotally attached to said yoke and having in its wall a longitudinal slot, a notched arc fixed to said yoke and having its center located on the pivotal axis of said handle, an engaging member

within said handle having an enlarged portion designed to fit close to the interior wall of the handle and a single-toothed portion designed to engage with the notches of the 6 arc, a sleeve surrounding said handle and riveted to said engaging member, the slot in the wall of said handle permitting said sleeve and the attached engaging member to be drawn away from said notched arc, and a 10 spiral spring within said handle bearing

against the rear end of said engaging member for automatically returning the single-toothed portion of the latter into engagement with the notched arc upon release of said sleeve. 15

In testimony whereof, I have signed my name to this specification this 23rd day of August, 1923.

VERNON B. PIKE.
